SEPARABLE FASTENER INSTALLATION

Moses F. Carr, Lexington, Mass., assignor to
United-Carr Fastener Corporation, Cambridge,
Mass., a corporation of Massachusetts

Application January 18, 1930. Serial No. 421,758

4 Claims. (Cl. 24—218)

My invention aims to provide improvements in separable fastener installations and particularly improvements in the attaching means of the installation.

5 Referring to the embodiment of my invention illustrated by the drawing:—

Figure 1 is a section showing one form of fastener installation to which my invention is applicable;

10 Fig. 2 is a section through an attaching cap showing the relation of the double wall to the other portions of the cap prior to the double wall being bent inwardly to form the clenching means; and

15 Fig. 3 is an under side view of the cap shown in Fig. 1.

Referring now to the drawing, which forms a part of this invention, I have shown a particular type of fastener element secured to a carrying medium in such a manner as to illustrate one particular application of my invention. It is to be understood, however, that my invention is applicable to many types of sockets, studs, buttons and the like and, therefore, the embodiment of 25 the invention shown is for illustrative purposes only.

In Fig. 1 of the drawing I have illustrated a well-known type of socket 1 having a fabric-engaging surface 2 engaged with one face of a 30 flexible carrying medium 3 and secured thereto by a rivet portion 4 pressed from the socket casing and extending through the carrying medium 3 into engagement with an attaching cap 5 located at the opposite side of the carrying medium.

The particular attaching cap 5 illustrated is pressed from a single piece of metal and has a central depressed portion 6 having an outwardly flaring wall 6^a beginning at the bottom of the 40 depression providing turning means against which the rivet portion 4 is forced and turned outwardly adjacent to the outer periphery of the turning means. Thus, the metal is pressed downwardly to form a double wall which is bent inwardly to provide clenching means 7 to prevent separation of the parts after they have been secured together, as clearly illustrated in Fig. 45 1. The metal of the attaching plate or cap 5 beyond the double wall portion is of substantial 50 area and may be of any desired shape. This metal provides a fabric-engaging surface 8 which cooperates with the fabric-engaging surface 2 of the socket or other element 1, thereby to grip the flexible carrying medium 3 between the attaching cap 5 and the socket 1.

One of the important features of my invention is in the location of the attaching means centrally of the two parts which are to be secured together. Heretofore, it has been the usual practice to provide the turning and clenching means on either the cap or the fastener element adjacent to the peripheral edge and provide attaching prongs or a tubular rivet for engagement therewith. With that type of attachment the carrying medium had to be penetrated relatively close to the edges of the parts and in many instances when the carrying medium was placed under lateral stress it would tear or pull loose from between the edges of the parts of the installation, thus exposing rough and unsightly portions of the carrying medium and weakening or ruining the attachment.

With my type of fastening means described above and illustrated in the drawing, regardless of whether or not the turning and clenching means is on the attaching cap or the fastener part, there is a decided advantage because the carrying medium is penetrated at a point relatively remote from the edges of the cap and fastener element. Furthermore, a substantial area of the carrying medium is gripped tightly between the two parts between the edges thereof and the penetrating element of the attaching means to provide a strong, durable attachment.

The fastening means which I have illustrated and described is relatively simple to manufacture and is so arranged that the parts of a given installation may be easily and quickly assembled.

While I have illustrated and described a preferred embodiment of my invention, it should be understood that I do not wish to be limited thereby, because the scope of my invention is best set forth in the following claims.

What is claimed,

1. A fastener member installation comprising, 95 in combination, a carrying medium, a snap fastener member for cooperative engagement with another snap fastener member and a one-piece attaching plate having an outer surface which extends from the periphery of the attaching plate in an upwardly curved direction for a substantial distance toward the center, annular anvil and clenching means located in the central portion of said attaching plate remote from the periphery thereof and a shank extending from said snap fastener member through the carrying medium and having its free end upset by and engaged with the anvil and clenching means of the attaching plate to secure the parts of the installation together.

2. A fastener member installation comprising, in combination, a carrying medium, a snap fastener member for cooperative engagement with another snap fastener member and a one-piece sheet metal attaching plate, said attaching plate having integral annular anvil and clenching means located adjacent to the center thereof and remote from the periphery thereof and having its outer edge turned under to provide a smooth portion of substantial width in engagement with the carrying medium, and a tubular rivet extending from said snap fastener member through the carrying medium and upset by and engaged with the anvil and clenching means of the attaching plate to secure the parts of the installation together.

3. An attaching plate for snap fastener and like installations comprising a central depressed portion surrounded by an outwardly flaring wall from the bottom of the depressed portion to provide turning means, an inwardly turned double wall portion, each portion contacting with the other and surrounding the wall of the central depressed portion to provide clenching means and to provide the attaching plate with a substantially continuous outer surface extending

from the periphery of the attaching plate in an upwardly and inwardly extending direction toward the center and a support-engaging surface of substantial width located between the inwardly turned walls and the periphery of the said plate.

4. An attaching plate for snap fastener and like installations comprising a central depressed portion having an outwardly flaring wall from the bottom of the depressed portion to provide turning means for upsetting attaching means provided by the snap fastener, an integral wall extending downwardly and inwardly from the periphery of said depressed portion, a second wall integral with said first wall and extending outwardly and upwardly in close proximity to said first wall to a point adjacent to the periphery of said depressed portion and said attaching plate having a portion of substantial area extending outwardly in all directions from said second wall adjacent to the periphery of said depressed portion thereby providing a relatively continuous smooth outer surface from the periphery of the depressed portion to the periphery of the attaching plate.
